UNITED STATES PATENT OFFICE.

SENECA RISLEY AND FORREST E. RUGER, OF BINGHAMTON, NEW YORK.

CHAIR HAVING ADJUSTABLE BACK.

No. 865,431.

Specification of Letters Patent.

Patented Sept. 10, 1907.

Application filed January 18, 1906. Serial No. 296,649.

To all whom it may concern:

Be it known that we, SENECA RISLEY and FORREST E. RUGER, both citizens of the United States, residing at Binghamton, in the county of Broome and State of 5 New York, have invented a new and useful Improvement in Chairs Having Adjustable Backs, of which the following is a specification.

Our invention relates to improvements in chairs having adjustable backs, in which the back is hinged or 10 fulcrumed to the base of the chair and supported by a traverse rod extending behind the back and engaging a rack in the arm of the chair or in a metallic plate attached thereto.

The objects of our invention are to provide a chair 15 with a movable back which may be fixed in any desired position by means of a rotatable rod provided with cranks at its ends, which cranks engage and disengage rack plates by means of a movable cam plate actuated, by a controlling rod bracketed to the arm of the chair. 20 We attain these objects by the mechanism illustrated in the accompanying drawing.

Figure 1 is a side view showing our improved mechanism for adjusting the backs of chairs when attached to same. Fig. 2 is a rear view of said chair; and Fig. 3 25 is an enlarged sectional side view, illustrating the principal parts of our invention. Fig. 4 is a detail view of our cam plate, by means of which we raise and lower simultaneously either end of the cranked supporting rod.

30 In the drawings, A represents the chair proper, the hinged back of which is raised by the tension spring "f", the tendency of which spring is to always carry the back toward an up-right position.

The rod "a¹" is cranked at either end and attached 35 to the back by staples, as shown in Fig. 2, which staples form bearings, in which the rod "a¹" rotates and which, by its extreme ends, forms dogs which engage the racks "b" "b", as shown in Fig. 2, and firmly support the back in the desired position.

40 The dog "a", which is a continuation of the rod "a¹", is carried out of the rack "b" by means of the controlling rod "d", which acts as a lever when acted upon by pressure of the hand at "d³", when the cam plate "c" is forced upwardly, carrying the dog "a" out of the

rack plates "b" "b", when the hinged back may be 45 pressed backwardly, or automatically carried forward by the tension spring "f", to the desired position, into which position the back is locked by releasing the controlling rod "d", which is carried forward by the coiled spring "d²," thus acting upon the cam plate "c", 50 which causes the dog "a" to descend and engage the rack "b".

It will be noted that the cam plate "c" is positive in its action, the dog "a" being carried downward and held in the rack by the upper portion of the cam 55 plate "c".

The slots "c¹" "c¹" in the cam plate "c", engage the guide posts "g" "g" and give proper alinement and support to the cam plate, when being acted upon by the controlling rod "d". The controlling rod "d" being pivoted to the cam plate "c", as shown in Figs. 1 and 3, passes through the eye of the bracket "d¹", between which and the knob "d³" is interposed a coiled spring "d²". When pressure by the hand is applied to the knob "d³", compressing the coiled spring "d²", the 60 rod actuates the cam plate "c", causing it to move upwardly upon the guide posts "g" "g" and raise the dogs "a" "a" from the racks "b" "b", when the occupant of the chair, by a proper movement of the body, causes the back of the chair to move to the desired position, when the dogs "a" "a" are made to descend and engage the racks "b" "b", by releasing the knob "d³". 70

"b¹" "b¹" represent iron dowel pins, by means of which the rack plates are attached to the chair. 75

What we claim as new and desire to protect by Letters Patent is:—

In a chair, a frame, a movable back connected thereto, a rotatable rod carried by the back, and provided with cranks at its ends, rack plates carried by the chair frame 80 and engaged by the said cranks, a movable cam plate carried by the rack plate and a controlling rod connected with the cam plate and bracketed to the frame of the chair for actuating the cam plate.

SENECA RISLEY.
FORREST E. RUGER.
